HOT WATER RADIATOR

Albert A. Haas, Macon, Ga.

Application December 15, 1938, Serial No. 245,963

4 Claims. (CL 219—39)

This invention relates to improvements in hot water radiators or heating structures and pertains particularly to a novel heating and air circulating device.

5 The primary object of the present invention is to provide an improved hot water heater or radiator wherein a novel means is provided for heating water in the radiator unit and circulating the water through the same and also circulating air through the unit in such a manner as to effectively remove the heat units from the 10 circulating water for discharge into the surrounding atmosphere.

Another object of the invention is to provide a 15 heater wherein a novel means is employed for raising the temperature of the heat carrying medium and there is also provided a novel means associated with the receptacle in which the heat carrying medium is confined, which operates as 20 a safety to permit the discharge of the heated medium from the receptacle in the event that the temperature of such medium is raised to a point where an unsafe pressure may be developed in the receptacle.

25 Another object of the invention is to provide a hot water radiator which has connected therewith as a unitary part thereof, an electric heating unit for raising the temperature of the water in the radiator and an electrical control 30 means for controlling the flow of current to said heating unit in accordance with the temperature of the atmosphere surrounding the radiator.

A further object of the invention is to provide 35 an improved hot water radiator which is designed to form a compact structure which may be readily moved about, thus making it possible to employ the structure in several different rooms or compartments.

A still further object of the invention is to provide 40 in a hot water heating radiator, a novel water receptacle structure and means associated therewith for circulating air through the structure so that the maximum heating efficiency of the radiator may be obtained.

45 The invention will be best understood from a consideration of the following detailed description taken in connection with the accompanying drawings forming part of this specification, with the understanding, however, that the invention is 50 not to be confined to any strict conformity with the showing of the drawings but may be changed or modified so long as such changes or modifications mark no material departure from the salient features of the invention as expressed in 55 the appended claims.

In the drawings:

Fig. 1 is a view partly in vertical longitudinal section and partly in elevation of the structure embodying the present invention, the same being viewed from the rear.

Fig. 2 is a vertical section taken on the line 2—2 of Fig. 1.

Fig. 3 is a horizontal section taken on the line 3—3 of Fig. 1.

Fig. 4 is a vertical section on the line 4—4 10 of Fig. 1.

Fig. 5 is a circuit diagram for the electrical units associated with the radiator.

Fig. 6 is a view in elevation of the thermostat control unit.

Referring now more particularly to the drawings, the numeral 1 generally designates the body proper of the radiator structure. This body 1 forms a water receptacle and is of generally rectangular contour and has a central open portion 2.

The body 1 is hollow so that there are formed the upper and lower chambers 3 and 4, respectively, and the connecting vertical chambers 5 which are filled with water. The inner walls of the rectangular receptacle are connected by the flat tubes 6 which open through the walls at their two ends and which are in the crossed relation shown so that they form a central honey-comb structure through which air may pass from one side of the radiator to the other. As shown in Fig. 1, these flat tubes have their ends connected by the nipples 7 with the walls of the chamber between which the tubes are disposed, the nipples extending through the walls and into the chambers so that water may freely pass from any one of the chambers into the tubes or pass out of any of the tubes into any of the chambers.

At the top of the body there is formed the upwardly extending nipple 8 which is closed by the threaded plug 9. This nipple is provided for hand filling the receptacle. One vertical side wall of the receptacle is provided with a sight opening or window 10 which is covered by a glass panel 11. This covered window is adjacent the top of the receptacle and thus serves as a convenient means for determining when the water in the receptacle is at an undesirably low point.

Within the lower chamber 4 the bottom wall 12 thereof has secured thereto a baffle 13 which 50 covers the inlet end of a water supply pipe 14. This pipe is provided with a suitable valve 15 by which the flow of water into the receptacle is controlled. By this means the heater structure may be connected with a regular house water system 55

and the nipple 8 need not be used for filling the heater.

Adjacent the top of the structure and preferably upon the side thereof remote from the water supply pipe 14, there is connected a nipple 16 which opens into the upper water chamber and which is connected with the casing of a relief valve which is indicated generally by the numeral 17, the casing being designated 18 and being divided, as shown in detail in Fig. 4, into upper and lower portions. The upper portion of the casing 18 has the reduced vertical extension 19 in the upper end of which is threaded a plug 20. This plug and the open upper end portion 19 of the casing is covered by a cap 21.

Secured between the two sections of the casing 18 is a flexible diaphragm 22 which carries a valve pin 23 which is pointed at its lower end, as indicated at 24 and is normally pressed into the outlet nipple 25 of the casing by the spring 26 which is upon the opposite side of the diaphragm 22 and exerts its expansive pressure against the fixed plug 20 and the yieldable diaphragm. The outlet 25 of the valve casing is connected with the overflow discharge pipe 27.

At one end of the chamber 4 the outer side wall is provided with a bossed opening 28 in which is threadably secured the head 29 of an electric resistance heating unit 30. This heating unit 30 extends longitudinally through the lower chamber 4 of the heating device, as shown in Fig. 1, and when energized heats the water contents of the receptacle. The operation of this heating unit is controlled by a suitable thermostatic unit which is indicated generally by the numeral 31 and which is of a type wherein the temperature at which it cuts in or out may be regulated. As shown in Fig. 6, the face of the unit is provided with a suitable dial and pointer 32 for regulating the responsive temperature for the thermostat. In view of the fact that this thermostat in itself forms no part of the present invention and may be of any standard make, no detailed illustration of the same has been made. As shown in Fig. 5, the thermostat 31 is in circuit with the heater unit 30 and suitable means is provided in the electric circuit in which these units are coupled, for manually opening and closing the circuit, such means being in the form of a switch of suitable design, indicated at 33.

The rear side of the water receptacle body 1 is suitably reinforced at the top and bottom, as indicated at 34, for the attachment thereto of a suitable frame 35 by means of bolts 36. These bolts are tapped into the reinforced body portions 34 of the receptacle so as to secure this frame 35 across the back thereof and over the honey-combed central area 2, as shown in Fig. 2. The frame structure 35 is designed for the support of an electric motor 37, the shaft 38 of which passes through a suitable opening in the supporting structure and carries upon its inner end the fan 39. The inner side of the frame structure 35 is covered with suitable insulation such as sheet asbestos or any other suitable insulation material, as indicated at 40. This insulation protects the motor from the heat of the radiator.

As shown in Fig. 5, the motor 37 is electrically connected across the circuit in which the heater and thermostat are connected and thus it will be seen that the motor is not controlled by the thermostat but can only be started or stopped by closing or opening the switch 33.

The water receptacle body 1 is disposed within a suitable cabinet or console which is generally

designated 41. This cabinet or console may be made of any suitable material and has the top and bottom walls 42 and 43, the side walls 44 and front wall 45. The back may be opened or closed as desired. The front and side walls of the console are provided with openings covered by screens or grill-work 46 while the top and bottom walls may be provided with ventilation openings 47. The console is here shown as being supported upon an underlying floor 48 by feet or legs 49, but obviously any suitable means may be employed for supporting the console and it is to be understood that the invention is not to be limited to this specific construction nor to the use of the feet 50, which are shown upon the bottom of the water heater for maintaining the receptacle in suitable spaced relation with the bottom wall 43 of the console.

From the foregoing, it will be readily apparent that in putting the radiator structure into use, the same is filled by opening the valve 15 to permit the water to flow into the lower chamber 4 and into the vertical and top chambers. After the water has reached the top of the upper chamber 3, the valve may be closed and if it is desired to put the radiator into operation immediately, the switch 33 may then be closed so as to energize the heating unit 30. The thermostat 31 should be previously set to the temperature desired for the room in which the heater is located. Upon the closing of the switch, the motor 37 will start to operate and will continue in operation so long as the switch is closed even though the heating unit may be cut off by the thermostat. If the pressure within the receptacle becomes greater than is safe, this will be transmitted into the safety valve casing 18 and effect the upward flexing of the diaphragm 22 against the tension of the spring 26, thus opening the drain pipe 27 and permitting the excess pressure to escape.

In addition to providing the manual circuit controller 33 whereby the operation of both the fan motor and the heater may be started or stopped as desired, it is desired to incorporate in circuit with the motor a rheostat such as is indicated at 51, by means of which the speed of the motor may be regulated or the operation of the motor may be completely shut off without affecting the operation of the heater 30, when the switch 33 is closed. This rheostat is illustrated as having three speed positions and is also constructed so that the switch blade can be completely disconnected with the resistance units and thus completely shut off the operation of the motor, without interrupting the operation of the heater, when desired.

While the console has been illustrated with supporting feet or legs, it is to be understood that these may be eliminated if desired, and the console structure mounted in any other suitable manner as, for example, it may be hung upon the wall or from the ceiling as may be found most desirable.

While the present device is intended primarily for use as a heating unit, it may also be used in the summer time as a cooling unit, the cooling action being accomplished by supplying the device from a city water line or other source of supply through the connection provided at 14 and then releasing the tension of spring 26 of the safety relief valve 17 so as to allow a small flow of water through the receptacle and out through the drain 27. The thermostat will also be adjusted by turning it back to a position where it will not close the heater unit circuit. By then

5 operating the circulation fan at the desired speed, the cool water flowing through the tubes 6 and the air circulated between the tubes by the fan, will result in the lowering of the temperature of the surrounding atmosphere.

What is claimed is:

10 1. A heating radiator of the character described, comprising a chambered body designed to contain a fluid to be heated, said chambered body being formed to provide a central open area, a plurality of fluid conducting tubes disposed across said open area, the tubes being in intersecting relation and having their ends opening through walls of the structure into the fluid 15 chambers thereof, an electric resistance heater disposed in one of said fluid chambers, control means for said heater whereby the operation of the same will be governed by a heat responsive device, said heat responsive device being in circuit connection with said heater and operating in response to variations in the atmosphere surrounding the radiator, and means for effecting a circulation of air across said tubes.

20 2. A heating radiator of the character described, comprising a water receptacle having top and bottom horizontally extending water chambers and vertically extending side water chambers connecting the top and bottom chambers whereby a central open area is defined by the chambers, a plurality of relatively wide and flat water conducting tubes extending across said area and having their ends opening through the walls of and into all of said chambers whereby water is carried along crossed paths between the 25 chambers and across said area, means for heating the water within the chambers, means for filling the chambers, an outlet for the chambers, and means disposed at one side of the radiator for effecting a forced circulation of air through 30 said area and across said tubes.

35 3. A heating radiator of the character described, comprising a water receptacle formed to provide upper and lower horizontal water

chambers and vertical side water chambers connecting the upper and lower chambers, the said chambers together defining a rectangle having a central open area, a plurality of water conducting tubes extending through said area, certain 5 of said tubes being in a group disposed to extend at an angle to a group making up the remaining tubes and each of said chambers having tubes of both groups opening thereinto, a valve controlled water supply pipe opening into 10 the lower one of the chambers, a pressure relief valve controlled outlet connected with the upper one of the chambers, an electrical resistance heating unit disposed in the lower one of the chambers for heating the contents of the 15 radiator, a supporting unit secured to one side of the radiator and extending over the said central area, an electric motor mounted upon said supporting unit and having a shaft extending therethrough toward said area, a fan carried 20 upon said motor shaft upon the side of the supporting unit opposite from the motor, and insulation material disposed over the inner side of said supporting unit, said fan when operating creating a forced circulation of air through said 25 area and across said tubes.

4. A heating radiator of the character described, comprising a water receptacle which is formed to provide upper and lower horizontal water chambers and vertical side water chambers, the said chambers together outlining a central open area, a plurality of flat water tubes extending diagonally in two directions across said area, said tubes having a width equaling the width 30 of said area, said tubes being in intersecting relation and each opening at its two ends into contiguous water chambers, means for introducing water into the receptacle, an outlet for the receptacle, means for heating the contents of 35 the receptacle, and means for circulating air through said area and across said tubes.

ALBERT A. HAAS.
